UNITED STATES PATENT OFFICE.

JULIUS PEGEL, OF PHILADELPHIA, PENNSYLVANIA, ASSIGNOR TO JOHN BROMLEY & SONS.

DESIGN FOR A RUG.

SPECIFICATION forming part of Design No. 20,373, dated December 9, 1890.

Application filed August 30, 1890. Serial No. 363,558. Term of patent 8½ years.

To all whom it may concern:

Be it known that I, JULIUS PEGEL, a subject of the Emperor of Germany, residing in the city of Philadelphia, State of Pennsylvania, have invented and produced a new and original Design for a Rug, of which the following is a full, clear, and exact description, reference being had to the accompanying drawing, forming a part of this specification.

10 My invention has relation to the surface ornamentation of a rug; and it consists of a design therefor, which is fully illustrated in the accompanying photographic drawing hereto annexed and to which reference is made.

15 It is obvious that the design consists of two segregable parts—namely, the bordering

proper (marked A,) and the center piece C, with its bordering, (marked B.)

I claim as my invention—

1. The design for a rug, substantially as shown and set forth.
2. The design for the border A of a rug, substantially as shown and set forth.
3. The design for the center piece C and its border B, substantially as shown and set forth.

In testimony whereof I have hereunto affixed my signature this 31st day of July, A. D. 1890.

JULIUS PEGEL.
